UNITED STATES PATENT OFFICE.

LOUIS STEIMBAN, OF NEW YORK, N. Y.

DISH-WASHING MACHINE.

1,086,626.

Specification of Letters Patent. Patented Feb. 10, 1914.

Application filed October 31, 1912. Serial No. 728,831.

To all whom it may concern:

Be it known that I, LOUIS STEIMBAN, a citizen of the United States, residing at the borough of Brooklyn, in the city of New York, county of Kings, and State of New York, have invented certain new and useful Improvements in Dish-Washing Machines, of which the following is a specification, reference being had therein to the accompanying drawings, which form a part thereof.

My invention relates to dish washing machines, and more particularly to a type thereof wherein a reticulated container for soiled dishes is adapted to be immersed in the cleaning fluid.

The main object of the invention is to provide a machine of this character wherein the dishes as they are immersed in the cleaning fluid will receive both vertical and lateral motion in a manner to bring said fluid into a more intimate relation with all of the dishes in the container, thus tending to more thoroughly and more rapidly cleanse the dishes.

A further object is to provide a machine of this character wherein the support for the container may be removed from above the cleansing bath in a manner to facilitate the mounting or removal of the container while at the same time avoiding the necessity for the operator to lean over the bath for this purpose.

A still further object is to provide a machine of this character wherein the support for the container will automatically descend into the cleaning bath and through its descent will have imparted thereto a rotative movement about a vertical axis in a manner to cause the fluid to pass both vertically and horizontally between the dishes. And a still further object is to provide a machine of this character wherein the vertical and lateral movement of the container may be repeated by means of a mechanism which will be conveniently accessible to the operator while at the same time permitting a rapid actuation of the support for the container.

The invention consists primarily in a dish washing machine embodying therein a tank

adapted to receive a cleaning fluid, a support for a container for soiled dishes, a bridge having a vertical bearing therein for said support, co-operating means carried by said bridge and said support whereby said support is adapted to receive simultaneous vertical and lateral movement, and manually operative means for raising and lowering said support in said bearing; and in such other novel features of construction and combination of parts as are hereinafter set forth and described, and more particularly pointed out in the claims hereto appended.

Referring to the drawings: Figure 1 is a side elevation of a machine embodying my invention; Fig. 2 is a front view thereof, and Fig. 3 is a detail of the mechanism whereby the vertical reciprocation is imparted to said support.

Like letters refer to like parts throughout the several views.

In the embodiment of my invention shown in the drawings, *a* indicates a tank adapted to receive cleaning fluid. Discharging into this tank are the hot and cold water pipes *b* and *c* and leading therefrom is a waste pipe *d* and an overflow pipe *e*. Projecting upwardly from the tank *a* are two oppositely disposed standards *f* and *g* suitably placed, and mounted upon the tops of these standards is a bridge *h* having therein a bearing *h'* for the reciprocating member of a support for a container for the dishes, and an interiorly threaded sleeve *h''* in vertical alignment therewith. Slidably mounted in the bearing *h'* is a sleeve *i* and rotatably mounted in said sleeve and held against axial movement therein by the collar *j* is a worm shaft *k* meshing with the threads in the sleeve *h''*. Upon the lower end of this worm shaft is mounted a collar *l* carrying hooks *m* adapted to receive the handle of a container for the dishes to be cleaned. The sleeve *i* is limited to a direct vertical movement and upon one face thereof is formed a rack *n* by means of which this sleeve and the shaft *k* may be simultaneously reciprocated so as to cause the sleeve *h''* to impart to said worm shaft a rotative movement simultaneously with this vertical reciprocating movement. Carried by the

bridge h are bearings o for the shaft p upon which shaft is mounted a gear wheel p' meshing with the said rack n . The shaft p is adapted to be rotated by means of a 5 crank handle p^2 . One end of the bridge h is pivotally mounted on its standard as f , while the other end thereof is provided with a suitable hook adapted to slide over and engage the other standard g . By this means 10 the entire bridge may be swung laterally of the machine so as to remove it from immediately above the tank in order to facilitate the application or removal of the dish container thereto or therefrom. The actuating mechanism being carried in its entirety by this bridge, it is possible to move 15 this bridge in the manner described without possibility of disarrangement of parts. Adjacent to one end of the machine is a 20 receiving table r .

To receive the dishes to be cleansed, I provide a container comprising a reticulated basket body s having a bail handle s' provided with a central looped portion s^2 adapted to pass over and snugly fit upon the hooks m . Secured to the looped portion s^2 is a 25 wooden handle s^3 which is used because of the low heat conductivity of this material. Mounted upon and passing through the 30 bearing h' is a set screw t having a handle t' , the function of which set screw is to lock the sleeve i in position relative to the bridge h .

The operation of the herein described device is substantially as follows: In using the 35 device, the sleeve i and worm shaft k are raised by means of the rack and pinion n p' so as to bring the hooks m adjacent to the bridge h . The said bridge is then swung 40 upon the standard f until said hooks are above the table r . The container s is then mounted upon the hooks m by means of the looped portion s^2 of the handle s' , and the bridge swung to its former position, the 45 hook of said bridge fitting over the other standard g . The set screw t which while the container is being mounted upon the hooks m is set to hold the sleeve i and worm shaft k in the raised position, is then released, the weight of the said container and 50 its contents causing them to descend into the tank a . The sleeve i during this descent moves merely vertically, but the shaft k through the engagement thereof with the interiorly screw threaded sleeve h^2 , rotates the said shaft and with it the container, thus causing the said container to have both a 55 vertical and a rotary movement upon entering the cleaning bath. The handle p^2 may 60 then be used to repeatedly raise and lower the sleeve i , the shaft k with the vertical movement of this sleeve having imparted thereto a simultaneous rotary movement so as to cause the cleaning bath to come into

contact with all portions of the dishes contained in the container in a manner to thoroughly cleanse same. 65

When the dishes have been thoroughly cleaned, the handle p^2 , shaft p , pinion p' and rack n are used to raise the container to 70 its original position, and the set screw t is set to hold it in this position. Thereupon the bridge h may again be swung laterally so as to bring the container above the drip table r where it may be conveniently removed 75 from the hooks m and the dishes be permitted to drain before removing to the drying table. The water pipes b , c , overflow pipe e and drain pipe d are used to control the quantity and temperature of the water in 80 the bath, and the wooden handle s^3 upon the container is for the purpose of permitting the convenient handling of this container when removing it from the bath, at which time the metallic portions of the container 85 would be extremely hot.

It will be observed that by the construction herein shown and described, not only may the container be quickly mounted upon the hooks m or secured in position in the machine, but that when once so secured the dishes may be violently agitated within the bath with the expenditure of but small energy on the part of the operator, and that by reason of the automatic simultaneous 95 vertical and rotary movement of the support for the container, the dishes may be more thoroughly and more rapidly cleansed than by a mere submersion thereof in the bath. 100

It is not my intention to limit the invention to the precise details of construction shown in the accompanying drawings, it being apparent that such may be varied without departing from the spirit and scope of 105 the invention.

Having described my invention, what I claim as new and desire to have protected by Letters Patent, is:—

1. A dish washing machine embodying 110 therein a tank adapted to contain a cleansing bath, a support for a container for soiled dishes, a bridge having a vertical bearing therein for said support, coöperating means carried by said bridge and said support, 115 whereby said support is adapted to receive simultaneous vertical and lateral movement, and manually operative means for raising and lowering said support in said bearing.

2. A dish washing machine embodying 120 therein a tank adapted to contain a cleaning fluid, a bridge having a vertical bearing and an interiorly screw-threaded bearing alined therewith, a support for a container including therein a vertically movable sleeve, 125 mounted in said vertical bearing, a worm shaft one end of which is rotatably mounted in and movable vertically with said sleeve,

and the other end of which is mounted in
said interiorly screw-threaded bearing, and
means carried by the lower end of said
worm shaft whereby a container may be car-
ried thereby, and manually operative means
for raising and lowering said sleeve and
said worm shaft.

5 In witness whereof, I have hereunto af-

fixed my signature, in the presence of two
subscribing witnesses, this 24 day of Octo- 10
ber, 1912.

LOUIS STRIMBAN.
